UNITED STATES PATENT OFFICE

117,636

DESIGN FOR AN AUTOMOBILE

Paul M. Lewis, Denver, Colo.

Application April 15, 1939, Serial No. 84,328

Term of patent 3½ years

To all whom it may concern:

Be it known that I, Paul M. Lewis, a citizen of the United States, residing at Denver, in the county of Denver and State of Colorado, have invented a new, original, and ornamental Design for an Automobile, of which the following is a specification, reference being had to the accompanying drawings, forming part thereof.

In the drawings:

Fig. 1 is a perspective view of an automobile showing the new design.

Fig. 2 is a plan view thereof.

Fig. 3 is a side view thereof.

Figs. 4 and 5 are front and rear views thereof, respectively.

I claim:

The ornamental design for an automobile, as shown.

PAUL M. LEWIS.
